UNITED STATES PATENT OFFICE.

JOHN D. BELANGER, OF CHICAGO, ILLINOIS.

COMBINATION-CHAIR.

1,277,682.

Specification of Letters Patent. Patented Sept. 3, 1918.

Application filed May 1, 1918. Serial No. 231,918.

To all whom it may concern:

Be it known that I, JOHN D. BELANGER, a citizen of the United States, and a resident of the city of Chicago, in the county of Cook 5 and State of Illinois, have invented a certain new and useful Improvement in Combination-Chairs; and I do hereby declare that the following description of my said invention, taken in connection with the accompanying sheet of drawing, forms a full, clear, and exact specification, which will enable others skilled in the art to which it 10 pertains to make and use the same.

My invention relates generally to improvements in chairs; and it consists, essentially, in the novel and peculiar combination of parts and details of construction, as hereinafter first fully set forth and described and then pointed out in the claims.

20 The object of my present invention is the production of an efficient and serviceable combined chair, baby's high chair, child's medium chair, and a step ladder, which by a simple manipulation can be readily 25 changed from one to the other device.

To accomplish this object, I construct this chair in the preferred embodiment of my invention, as illustrated in the drawings forming a part of this specification, and in 30 which Figure 1 is a perspective view of the furniture when in condition for use as a step ladder, no attention being given to minor details of construction which are correctly shown in other figures, Fig. 1 of the 35 drawings being intended merely to show, in a general way, the appearance of the chair. Fig. 2 is a side elevation of the same. Fig. 3 is a rear, and Fig. 4 a front elevation thereof. Fig. 5 is a front elevation of this 40 furniture when arranged as a common dining room, sitting room, or standard chair. Fig. 6 is a side elevation of the same. Fig. 7 is a similar view of a baby's high chair. Fig. 8 is a like view showing the chair as 45 a child's or medium high chair. Fig. 9 is a detail sectional view on an increased scale, of a portion of the chair, on line 9—9 of Fig. 4. Fig. 10 is a side elevation of the upper portion of the chair when arranged 50 as a high chair. Fig. 11 is a similar view of the upper portion of the chair showing the child's tray turned over to serve as a step for a step ladder. Fig. 12 is a plan of a fragment of the device illustrated in Fig. 55 11. Fig. 13 is a perspective view of a de-

tail of the chair; and Figs. 14 to 17 inclusive, are detail views of a pair of hinges by which the foot-board for a baby is pivoted to a part of the chair.

Like parts are designated by the same 60 characters and symbols of reference in all the various figures.

This chair comprises in its make-up as a standard, or common, chair, two front legs 12, 12^a, two rear legs 13, 13^a, the upper ends 65 of which form the back A, of the chair, and a seat proper B. The front legs 12, 12^a, are strongly connected by, preferably, a single, wide, rail 14, in the upper margin of which there is an excision 15, the object of which 70 will hereinafter appear, said rail 14 serving as a support for a foot board 22, for the high chair, and also as a tread for the step ladder.

Two rails 16, 17, and 16^a, 17^a, connect the 75 front and rear legs at the sides, and a single rail 18, connects the rear legs near their lower ends. The back of the chair includes a top rail 19, a medial rail 20, and two, spaced-apart, vertical, slats 21, connecting 80 the top and medial rails.

Resting upon the rails 17, 17^a, and the notched front rail 14, there is the foot board 22, at the right and left margins of which there are pivotally connected to said foot 85 board by hinges 23, upright posts 24, 24^a, which, at their upper ends, are hingedly connected to horizontally disposed bars 25, 25^a, which bars are, at their opposing ends connected to the face of the seat B, by 90 hinges, dowels, or otherwise, not shown, the hinges that connect the upper ends of the uprights to the bars 25, 25^a, being shown in Figs. 1, 8, and 9, at 26.

Rising from the horizontal bars 25, 25^a, 95 there are posts 27, 27^a, the upper ends of which are affixed to horizontally disposed rails 28, 28^a, which rails likewise extend, and are affixed to, the face of the seat B. At the forward ends of the rails 28, 28^a, there is 100 movably located an element C, which, in the position shown in Figs. 7 and 10, serves as a tray, while when in the position shown in Figs. 1, 2, 4, 8, and 11, this element C functions as a tread for a step ladder. This 105 element C is removable from the horizontal bars 28, 28^a, in a peculiar manner. Thus, at the forward ends of the rails 28, 28^a, there are secured loops 29, best seen in Figs. 10, 11, and 12, and adjacent the ends of the 110

tray C, there are straps 30, which straps are constructed to enter the loops 29 either from their front or their rear. At the ends of the tray C there are pivoted, upon pivots 31, 5 straps or bars 32, which bars pass through box-loops 33, which box-loops have pivots 34, on which they may rotate. When this element C is turned over, as shown best in Figs. 11 and 12, and then the tray pushed 10 forwardly, so that the straps 30 enter the loops 29 from the rear, the tray is held in this upturned position, the bars 32 extend downwardly, and are locked in the depending position by being placed behind buttons 15 35, located on the arm rests 25, 25^a, which prevents the tray C from moving rearwardly. By releasing the bars 32 from the buttons 35, the tray C may be liberated and either placed in position to serve as a child's 20 tray, or it may be placed out of the way above the chair seat B, as illustrated in Fig. 8, when the chair is to be used as a children's medium high chair.

The seat proper of this chair is, preferably, a substantially rectangular frame provided with a suitable seat bottom B^a, which may be wood veneer, cane, or other desirable material. This seat frame is pivotally connected to the chair-back by hinge members 36, best illustrated in Fig. 9, and having pins 37, passing through the side members of the chair-back, there being in these side-members, near their upper ends, elastic bumpers 38, against which the seat frame 35 may bear when placed into approximately vertical position.

Between the uprights 24, 24^a, there is pivoted a foot board D, by means of a peculiar hinge construction shown in detail in Figs. 40 14 to 17 inclusive, and comprising two members 39, which are secured at the outer ends of the foot board, and two additional members 40, secured to the uprights 24, 24^a. The member 39 has at one end a sidewise extending lug 41, which when the foot board 45 is turned down for use, strikes the backs of the uprights, and thereby sustains the foot board D in horizontal position, while when said foot board is turned into approximately vertical position, it strikes a stop pin 50 42, as illustrated in Fig. 2, and is thereby prevented from further backward movement.

At the forward ends of the arm rests 25, 55 25^a, there is located a tread board E; and behind the posts 27, 27^a, there is located a seat board 43, which tread board E and seat board 43, serve as a seat when the chair is to be used as a high chair, as illustrated in 60 Fig. 7, while the element E also serves as a tread when the chair is converted into a step ladder.

In order to describe the operation of this combination furniture, let it be assumed that 65 the chair is in a knocked-down condition to

function as a standard chair, and is to be turned into a baby's high chair, as shown in Fig. 7, the operator places one foot into the excision 15 in the front rail 14, and lifts the foot board 22 so that pins 44 thereon will 70 clear the front rail 14, and then taking hold of the seat proper swings the same into approximately vertical position as illustrated in Fig. 2. He or she now manipulates the tray C so as to extend from the front of 75 the rails 28, 28^a, and then swings the auxiliary foot board D into horizontal position, as depicted in Fig. 7, in which case the infant is placed upon the seat comprising the elements E and 43, while the rails 28, 28^a, 80 serve as arm rests to the occupant of the chair. To convert this chair into a step ladder, the auxiliary foot board D is turned into approximately vertical position, and the tray into the reversed position shown in 85 Figs. 2, 4, and 11, in which condition the foot board 22, the tread board E, and the element C serve as the steps for the step ladder.

When the chair is to be used as a medium high chair, the tray C is removed and placed into the position illustrated in Fig. 8, and the foot board D turned into vertical position, the child being seated upon the members E and 43, as hereinbefore mentioned. 90

To convert the chair from a high chair to a standard chair, it is first placed into the condition of a step ladder and then the seat turned down, in which case all the parts attached to the chair seat proper will swing 100 down with it and occupy the positions shown in Figs. 5 and 6.

For the purpose of strengthening the chair, brace-rods 45, may extend from the front legs to the chair-back, preferably diagonally, a construction, though desirable, is, however, not absolutely essential, and may be dispensed with, if desired. And for the purpose of adding to the appearance of the chair when used for any purpose but a 105 standard chair, I provide the back of the seat which under these conditions is toward the front, with either an upholstered cushion 46, or a plush, carpet, or other fabric covering, as may be desired or preferred. 110

It is, perhaps, obvious that wood is the natural, and preferred material from which to construct this chair; but it is also obvious that fiber, iron, or other material may be wholly, or partly, employed in the construction of this chair. 115

I have hereinbefore described with considerable minuteness the preferred embodiment of my invention, but I desire it to be understood that I am aware that details of 120 construction may be changed, and parts omitted without departing from the scope of my invention as defined in the appended claims.

Having thus fully described this inven- 125

tion, I claim as new, and desire to secure to myself by Letters Patent of the United States—

1. In a chair of the nature described, a pair of front legs, a pair of rear legs, said rear legs being upwardly extended to form the back of the chair, said legs being connected by bars and rails to afford a fixed structure, a seat proper, said seat being pivotally connected to the rear legs to swing upwardly, a foot board movably placed between said front legs, a pair of uprights hingedly connected to said foot board, a pair of arm-rests fixedly secured to the bottom-side of said seat proper, said uprights being hingedly connected to said arm-rests at the forward ends thereof, a foot board at the forward ends of said arm-rests, uprights fixed to, and extending from, said arm rests, rails fixedly connected to said uprights at one of their ends and to the back of the seat proper at their other ends, and a movable element at the ends of, and supported by, said rails.

2. In a chair of the nature described, a pair of front legs, a pair of rear legs, said rear legs being upwardly extended to form the back of the chair, said legs being connected by bars and rails to afford a fixed structure, a seat proper, said seat being pivotally connected to the rear legs to swing upwardly, a foot-board movably placed between said front legs, a pair of uprights hingedly connected to said foot-board, a pair of arm-rests fixedly secured to the bottom-side of said seat proper, said uprights being hingedly connected to said arm-rests at the forward ends thereof, a foot-board at the forward ends of said arm rests, uprights fixed to, and extending from said arm-rests, rails fixedly connected to said uprights at one of their ends and to the back of the seat proper at their other ends, and a movable element at the ends of, and supported by, said rails, said movable element being a tray-like structure, said structure having means for movably, but irremovably connecting said structure to said rails.

3. In a chair of the nature described, a chair-frame, a seat hingedly connected to said chair-frame, rails fixedly connected to the bottom-side of said seat, and a tray, said tray having a rod on each side approximately medially thereof and pivotally connected thereto at one end, a box-loop at each rail through which said side-rods are passed, said box loops having each a pivot

projecting from the back thereof and engaging said rail and rotating therein, and means on said tray for movably connecting 60 said tray to the free ends of said rails.

4. In a chair of the nature described, a chair-frame, a seat hingedly connected to said chair-frame, rails fixedly connected to the bottom side of said seat, and a tray, said tray having side-rods pivotally connected thereto at one end, a box-loop pivotally connected to each rail through which said side-rods are passed and means for movably connecting said tray to the free ends of said 70 rails, said latter means including loops at the free ends of said rails, and bars at the ends of said tray constructed to enter said loops in normally extended, and in reversed, upturned, positions.

5. In a chair of the nature described, a chair-frame including a wide, notched, front-rail, a seat proper, said seat proper being pivotally connected to said chair-frame at its lower end, a pair of arm-rests 80 fixedly secured to the bottom side of said chair-seat, a pair of uprights pivotally connected to the free ends of said arm-rests, a foot-board, said foot-board being normally supported by said wide, notched, front-rail, 85 said foot-board being hingedly connected to the lower ends of said uprights, stop-pins on said foot-board and normally engaging said wide, notched, front-rail to lock the said parts in erected position.

6. In a chair of the nature described, a chair-frame, including a wide, notched, front-rail, a seat proper, said seat proper being pivotally attached to said chair-frame at its lower end, a pair of arm-rests fixedly 95 connected to the bottom side of said chair-seat, a pair of uprights pivotally connected to the free ends of said arm rests, a foot-board, said foot-board being normally supported by said wide, notched, front-rail, said 100 foot-board being hingedly connected to the lower ends of said uprights, stop-pins on said foot-board and normally engaging said wide, notched, front-rail to lock said parts in erected position, and an auxiliary foot-board above said first mentioned foot-board, said auxiliary foot-board being pivotally connected to said uprights, means for sustaining said auxiliary foot-board in normal position, and means for retaining said auxiliary foot-board in inoperative position.

In testimony that I claim the foregoing as my invention I have hereunto set my hand.

JOHN D. BELANGER.
